J. ROSENBERG.

RULE FOR PRINTING INTERSECTING LINES.

APPLICATION FILED APR. 5, 1916. RENEWED JULY 16, 1917.

1,262,848.

Patented Apr. 16, 1918.

INVENTOR:

James Rosenberg,
BY Albert H. Baker,
ATTY:

UNITED STATES PATENT OFFICE

JAMES ROSENBERG, OF CLEVELAND, OHIO.

RULE FOR PRINTING INTERSECTING LINES.

1,262,848.

Specification of Letters Patent. Patented Apr. 16, 1918.

Application filed April 5, 1916, Serial No. 89,081. Renewed July 16, 1917. Serial No. 180,938.

To all whom it may concern:

Be it known that I, JAMES ROSENBERG, a citizen of the United States, residing at Cleveland, in the county of Cuyahoga and State of Ohio, have invented a certain new and useful Improvement in Rules for Printing Intersecting Lines, of which the following is a full, clear, and exact description, reference being had to the accompanying drawings.

This invention relates to rules for printers' use, enabling the printing of intersecting or abutting lines. The object of the invention is to provide a system of rule-printing members, which, while being simple and inexpensive to construct, shall enable the printing of a great variety of ruled forms with crossing or abutting lines which closely join each other. One of the difficulties in printing ruled lines by the devices commonly in use, is to bring the horizontal and vertical lines close enough together where they are intended to cross or abut. A space at such crossing point, which is a frequent incident to printing ruled lines, is an undesirable feature, while to avoid it has frequently led to the use of the more expensive method of making the copies by a ruling machine instead of by a printing press. My invention is in the nature of an improvement on the device for printing intersecting lines shown and claimed in my Patent No. 1,118,951, issued December 1, 1914. It is designed to increase the adaptability of the rule-printing device there shown, and enable the intersecting or abutting lines to come closer together.

In accomplishing the desired result, I form vertical grooves in one of the printing rules, the grooves being of such width that the relatively transverse rules may seat therein, and I form on the end of such transverse rule at the top an overhanging portion which may lie above the body of the grooved rule and carry the transverse printing line close to that of the grooved rule. I may also form a shoulder on the end of the transverse rule which may lock with a shoulder on the grooved rule, whereby one holds the other down. These, and other features, will be hereinafter more fully explained and summarized in the claims.

The drawings illustrate preferred embodiments of my invention. Figure 1 is a perspective of several of the rules assembled to print a suitable box form. In this

view are shown certain grooved rules and rules transverse thereto. Fig. 2 is a side elevation of one of the transverse rules; Fig. 3 is a cross section of the rule shown in Fig. 2; Fig. 4 is a side elevation of one of the grooved rules; Fig. 5 is a vertical section through one of the grooved rules, showing portions of two transverse rules in elevation; Fig. 6 is a plan of the rules shown in Fig. 5; Fig. 7 is a side elevation, partly broken away, of a transverse rule, wider than the rule shown in Fig. 2; Fig. 8 is an end view, and Fig. 9 a plan, of the rule shown in Fig. 7.

Fig. 1 is made up of various rules selected and arranged to illustrate the different features of the invention. In this view A indicates a border rule; B an intermediate rule parallel therewith; C rules transverse of the rules A and B and abutting them at their ends; C' another transverse rule abutting the rule B opposite one of the rules C, and C² a wider form of transverse rule abutting the grooved rule B. D indicates a brace rule which is not high enough to print but braces the transverse rules C.

The rule A is formed with a beveled top providing a narrow printing edge *a*, and vertical grooves *a'* formed in one side. These grooves are of less depth than half of the thickness of the rule so that their upper ends terminate within the beveled top at one side of the printing edge *a*. Any of the rules may be arranged to be reversible, so that they can print on either edge or may print on only one edge, as desired. I have illustrated at *a'* the bevel on the bottom edge of the rule A, and this is to be taken as illustrative of bevel on this edge of any of the rules, if desired.

The rule B is shown as having a top printing edge *b*, vertical grooves *b'* formed opposite to each other in opposite sides of the rule, and a through slot *b*² formed by cutting out the lower part of the intermediate portion of the rule between the grooves. Thus the lower portion of the rule B consists of teeth separated by slots, while the upper portion is continuous but has grooves in its opposite sides.

The rules C, C', C², are formed with printing beveled edges *c*, and with lips *c'* at the top overhanging at the ends. These lips are adapted to stand above the beveled tops of the rules A, B and thus

carry the printing line c close to the printing lines a or b . The width of the rules C and C' is the same as that of the grooves a' or b' , so that the ends of these rules may 5 seat in these grooves.

Where the grooved rule has a continuous groove in one side, as in the case of the rule A, the end of the rule C is formed as shown at the right-hand end of the rule C in Fig. 2. That is, the end is straight with the exception of the overhanging lip c' . If, however, the grooved rule has a slot through its lower portion, or has the lower part of the groove of deeper depth, the abutting end 10 of the transverse rule C may be formed with a projecting shoulder, as shown at c^2 in Fig. 2. The amount of the projection of these shoulders c^2 may be substantially half that of the width of the rule B, so that when 15 two of these rules C are placed in alinement on opposite sides of the rule B, their shoulders c^2 will substantially abut each other, as shown in Fig. 5. The overhang of the lips c' is less than that of the shoulders c^2 , so 20 that the ends of these lips may come close to the printing edge b but not interfere with it.

For convenience of illustration I have shown the rules C in Fig. 2 as having a 30 shoulder c^2 on one end and the other end continuously vertical from the bottom to the lip c' . It is to be understood, however, that either end of this rule may be made in either of these forms.

35 The rule C² (Figs. 1, 7, 8 and 9) is similar to the rule C, but wider. Under these circumstances there is a reduced portion c^3 at the ends, which may also carry the projection c^2 . Accordingly the rules B may be 40 made with their grooves and slots of standard dimensions, while the transverse rules may be of varying width and thus coact with type or furniture of different standard bodies and still seat at their ends in the 45 grooves and slots of the same rules B.

D, in Fig. 1, illustrates a bracing rule. This rule may be formed similar to the rule B, but not so high, and is shown as turned the other side up. That is to say, it has 50 grooves d' in its opposite sides and through slots d^2 in its upper portion, which leave tongues between them, the lower portion of the rule being continuous. A vertical notch c^4 in the lower portion of the rule C is 55 adapted to straddle the continuous portion d of the bridge rule, the adjacent portions of the rule C occupying the grooves d' and the slot d^2 .

With a set of rules like those indicated at A and B, and with transverse rules C 60 of various lengths, all sorts of box forms may be readily made up and locked together. In the arrangement shown the shoulders c^2 prevent the transverse rules rising in the form, so that if the grooved 65 rules are suitably locked in place, the others will be held down. The brace rule serves to prevent shifting or spring of the rule C, in case the grooved rules are a considerable 70 distance apart.

This system of rules may be easily taken apart and readily assembled. When assembled, they may print substantially continuous intersecting lines. Fig. 6 illustrates the close proximity of the ends of the rule 75 lines c , on the tops of the rules C and C', to the rule line b and the top of the rule B.

Having thus described my invention, what I claim is:

1. The combination of a printing rule 80 having vertical grooves formed in its side, the lower portions of said grooves being made into a deeper recess than the upper portion, combined with a transverse rule adapted to abut the side of the rule mentioned, and at its end occupy a groove there- 85 of and having a projecting shoulder at such end which occupies such deeper recess.

2. In a device of the character described, the combination of a printing rule having 90 oppositely positioned grooves in its opposite sides and having slots in its lower portion, merging with and connecting the grooves, the upper portion of said rule being beveled on opposite sides to present an intermediately located printing line, and transverse rules on opposite sides of the grooved rule and having their ends occupying the grooves thereof and having on the lower 95 portions of their ends projecting shoulders 100 which extend into said slots, the upper portions of said transverse rules overhanging the end thereof and adapted to lie above the bevel of the groove.

3. As a new article of manufacture, a 105 printing rule having its end portion reduced to provide a projecting rib narrower than the body of the rule and having its top portion overhanging the end, there being a printing surface at the extreme top of the 110 body of the rule and of such overhanging portion.

In testimony whereof, I hereunto affix my signature.

JAMES ROSENBERG.
